CLAIM

The ornamental design for a “telecommunication apparatus”, as shown and described.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings depict parts of the telecommunication apparatus that form no part of the claimed design. The surfaces shown between the broken lines and the solid lines form no part of the claimed design.

1 Claim, 3 Drawing Sheets(56)
